UNITED STATES PATENT OFFICE.

CARY C. WILDER, OF DENVER, COLORADO.

GARBAGE AND ASH RECEIVER.

966,145.

Specification of Letters Patent. Patented Aug. 3, 1910.

Application filed July 3, 1909. Serial No. 505,736.

To all whom it may concern:

Be it known that I, CARY C. WILDER, a citizen of the United States, residing at Denver, in the county of Denver and State of Colorado, have invented certain new and useful Improvements in Garbage and Ash Receivers, of which the following is a specification, reference being had therein to the accompanying drawing.

10 This invention relates to sanitary garbage, ash, and other receptacles, and the principal object of the same is to provide a receptacle which may be sunk within the ground and which is provided with a novel type of lid or cover by means of which all odors are prevented from escaping from the receptacle.

20 Another object of the invention is to provide a receptacle or container in which the refuse is kept in a pail supported within said container and which is sealed by the lid or cover thereof.

25 Still another object of the invention is to provide the pail with a novel type of bail attaching ears by means of which the bail thereof is connected to the interior of the pail and which, when not in use, may be forced within the pail so that it will not interfere with the closing movement of the 30 said lid or cover.

35 Other and further objects and advantages of the invention will be readily apparent from the following detailed description when taken in connection with the accompanying sheet of drawing wherein a preferred and practical embodiment of the invention has been shown.

40 Referring to said drawings—Figure 1 is a perspective view of the sanitary refuse receptacle, the lid or cover thereof being shown opened. Fig. 2 is a central vertical sectional view, the lid or cover being shown closed. Fig. 3 is a fragmentary sectional view of an upper portion of the pail showing 45 the manner of forming the bail receiving ears thereon.

45 Referring to said drawings by numerals, 1 designates a container preferably cylindrical and having an open bottom the edge of 50 which is thickened as indicated at 2 to reinforce the same. The top portion of the container is also reinforced adjacent its edge, as indicated at 3. An arm 4 projects outwardly and upwardly from said upper reinforcement 3, the upper portion of said arm extending vertically and in the same plane

as the body of the container and forms a stop 5, as will presently appear. The free upper end of said arm is thickened and rounded and is grooved at its central portion to form a pivot 6.

A lid or cover 7 is adapted to seal said upper end of the container 1, said lid or cover being provided with an outwardly extending reduced portion 8 arranged in the same plane as the lid or cover, the end of said reduced portion being weighted as indicated at 9, said weight preferably being formed by increasing the thickness of the material so that the same depends from the bottom of the end of said reduced portion. The intermediate portion of the under surface of said reduced portion is provided with a pendent pivot ear 10 adapted to surround the pivot 6. Directly opposite the 75 said reduced portion of the lid or cover, the edge thereof is provided with a pendent integral spring latch 11 the end portion of which is bent open itself and inturned to form a lid-lifting handle 12.

80 A refuse pail 13 the body of which may be of the usual tapering formation has its upper edge outturned to form an outstanding annular holding flange 14 which engages over the upper edge of the container 1 so that said pail may be supported in a pendent position within said container. Adjacent the upper edge of said body of the pail, the material thereof is slotted and bent inwardly to provide oppositely disposed bail 90 ears 15 each having an opening 16 through which the hook-shaped ends 17 of the bail 18 is attached. The bail 18 may be of the usual wire rod or other suitable material and is of such a size that it may be readily rocked 95 on its pivotal connection with said ears to permit it to be placed within the pail and out of the way of the lid or cover of the container when the same is closed onto the holding flanges of said pail, as clearly 100 shown in Fig. 2.

105 It will be seen from the foregoing that if desired the container may be sunk into the ground with its upper portion substantially flush with the surface thereof so that the pail 13 may be readily removed therefrom when the cover is raised. It will also be seen that when said lid or cover is raised, the outstanding weight thereof will contact with the stop 5 so as to limit the opening movement of said lid or cover. Another prominent feature of the invention is in the man-

ner of forming the bail ears for the pail 13. It will be readily seen that by projecting the same inwardly a simple and cheap means is provided for disposing of said bail 5 when not in use so that the same will not interfere with the closing of the lid or cover of the container. And as suggested in Fig. 3 the slotted portion of the body of the pail may be reinforced by means of the external 10 plates 19 which cover the openings therein caused by forcing the ears inwardly.

As will be seen by reference to Fig. 2 of the drawing, the holding flange 14 projects beyond the body of the container and forms 15 a latching lip over which the spring latch of the lid or cover "snaps" when said lid or cover is closed.

What I claim as my invention is:—

A device of the character described comprising a container, an arm projecting out- 20

wardly and upwardly therefrom and carrying a pivot at its outer end, a lid or cover having an outstanding pivot ear adapted for engagement with said pivot, a weighted pendent portion adjacent said pivot ear and 25 adapted to contact with said arm to limit the opening movement of said lid or cover, a latch carried by said lid or cover, diametrically opposite said hinge, and a pail provided with an annular flange to suspend 30 said pail from the upper edge of said container, said flange to be engaged by said latch to retain said lid or cover closed.

In testimony whereof I hereunto affix my signature in presence of two witnesses.

CARY C. WILDER.
